LASTING MACHINE

Lloyd G. Miller, Beverly, Mass., assignor to United Shoe Machinery Corporation, Flemington, N. J., a corporation of New Jersey

Application March 23, 1946, Serial No. 656,676

17 Claims. (Cl. 12—14)

1

This invention relates to lasting machines, and is herein shown as applied to a power-operated toe-lasting machine which, except as hereinafter noted, may be assumed to be constructed generally as disclosed in United States Letters Patent No. 2,160,846, granted on June 6, 1939 on an application of F. C. Eastman's and A. F. Pym's. It is to be understood, however, that the invention is not thus limited in its applicability.

The machine shown in the above-mentioned Letters Patent includes in its organization wipers movable heightwise of a last to perform what is commonly known as an upwiping operation on the toe end of an upper on the last and movable thereafter to wipe the marginal portion of the upper inwardly over an insole on the last, and also grippers which apply a pull to the toe end of the upper and control it in the course of the toe-lasting operation. The present invention provides, instead of such grippers, novel means including a device having the function of what is commonly known as a retarder for clamping the marginal portion of the upper on the wipers to cooperate with them in pulling and controlling the upper. In accordance with a feature of the invention, the retarder is so positioned initially as to serve by contact with the last as an end gage for the shoe when the shoe is presented to the machine, after which it is moved heightwise of the last by the wipers in the upwiping operation. In the construction shown the retarder thus not only positions the shoe lengthwise but also positions its extreme toe end laterally. In this and other aspects the invention has more particularly in view the adaptation of the machine for the lasting of shoes of that type in which the insole has a substantially plane bottom face over which the toe end of the upper is lasted, without any upstanding lip as in welt shoe work by engagement with which the shoe may be positioned lengthwise and laterally in the manner disclosed in the above-mentioned Letters Patent. As more particularly herein illustrated, the retarder is mounted on a support which is swung heightwise of the last in the upwiping operation about an axis located opposite the bottom of the forepart of the shoe by the action of the wipers on the retarder, and after the upwiping operation the support is swung still farther about that axis to withdraw the retarder from the wipers by cam-operated mechanism connected thereto. In combination with the retarder the invention also provides a holdown for pressing the marginal portion of the toe end of the insole on the bottom of the last, preferably until just after the wipers have started

2

their movements to wipe the upper inwardly over the insole, the construction shown being such that the holdown is withdrawn from the insole at the proper time by the same mechanism which withdraws the retarder from the wipers as above described, the holdown swinging about the same axis as the retarder support.

The novel features of the invention, including various novel details of construction and combinations of parts, will now be more particularly described with reference to the accompanying drawings and thereafter pointed out in the claims.

In the drawings,

Fig. 1 is a view in right-hand side elevation of a portion of the machine shown in the previously mentioned Letters Patent as modified for purposes of the present invention, with parts broken away;

Fig. 2 is a similar view on a larger scale of a portion of the structure shown in Fig. 1;

Fig. 3 is a view in rear elevation of the structure shown in Fig. 2, with parts in section;

Figs. 4, 5, 6 and 7 are views mainly in vertical section lengthwise of the shoe showing the retarder and the holdown and parts associated therewith as they appear at different times in the course of the operation of the machine;

Fig. 8 is mainly a plan view with parts in section on the line VIII—VIII of Fig. 6, the parts being shown in the same positions as in Fig. 6; and

Fig. 9 is a perspective view showing the toe-end portion of a shoe as it appears after the operation of the machine.

For positioning a shoe of the above-mentioned type heightwise in the machine there is provided a plate 2 arranged to engage the bottom face of the forepart of the insole, this plate preferably having, as shown, an insole-engaging face curved generally in accordance with the curvature of the bottom face of the forepart of the last when that face of the last has such a curvature. Instead of being so formed and arranged as to permit the marginal portion of the upper which is lasted inwardly over the insole to lie throughout its width in generally parallel relation to the bottom of the last, the plate as shown is of such a size and shape and is in such relation to the edge of the insole that a portion of the margin of the upper is lasted against it in upstanding relation to the shoe bottom, as illustrated in Fig. 7, so that this upstanding portion of the upper may later be readily trimmed off, the portion of the upper between the plate and the edge of the insole being preferably secured to the insole by cement applied prior to the lasting operation. On the upper por-

tion of the plate is a flange 3 which tends to bend the edge of the upper outwardly when the upper is pressed against the plate. The plate is supported on a holder 4 against the lower face of which it is positioned, this holder being formed on the lower end of a vertical rod 6 (Fig. 1) adjustable in directions heightwise of the shoe by a member 8 in the same manner as a similar rod shown in the previously mentioned Letters Patent. For positioning the plate 2 lengthwise and laterally on the holder 4 the holder is provided with two pairs of segmental lugs 10 (Figs. 4 and 8) which extend downwardly and fit within holes 12 in the plate. The plate is retained in the position determined by these lugs by means of a slide 14 mounted for movements in directions lengthwise of the shoe in a guideway in the holder 4, this slide having secured thereto a vertically extending plate 16 provided with a pair of L-shaped fingers 18 extending downwardly between the segmental lugs 10 into the holes 12 in the plate. Formed on the slide 14 is a knob 20 into which extends a screw 22 threaded in the holder 4, and mounted on this screw is a spring 24 which tends to move the slide toward the right with reference to Fig. 4. By means of this spring, therefore, the ends of the fingers 18 are pressed against the plate 2 within the holes 12 and by such frictional engagement with the plate hold the latter in position on the lugs 10. When it is desired to remove the plate 2 and to substitute a plate of different shape or size, all that need be done is to pull on the knob 20 and thus to move the slide 14 against the resistance of the spring 24 to relieve the pressure of the fingers 18 on the plate.

Shortly after the beginning of a cycle of power operations of the machine the shoe is clamped against the plate 2 by an upwardly movable toe rest 26, and a heel rest (not shown) is moved into engagement with the heel-end face of the shoe to hold it more securely against lengthwise displacement, as disclosed in the previously mentioned Letters Patent. Thereafter the toe-lasting operation takes place, the machine being provided for this purpose with a pair of cam-operated wipers 28 which are advanced bodily lengthwise of the shoe and are swung or closed inwardly widthwise of the shoe to embrace the upper closely about its toe-end portion and are swung upwardly about an axis (not shown) extending widthwise of the shoe to wipe the upper heightwise of the last, i. e., to perform the upwiping operation. After the upwiping operation the wipers are further advanced and closed to wipe the marginal portion of the upper inwardly over the insole. The wipers and their operating mechanisms may be assumed to be of substantially the same construction as disclosed in the above-mentioned Letters Patent, except that the cams for advancing and closing the wipers are preferably so formed as to move them farther inwardly over the insole than in operating on shoes of the welt type.

For purposes of this invention the upper-pulling grippers and their operating mechanisms shown in the abovementioned Letters Patent are omitted, and there is provided instead a retarder 30 for clamping the marginal portion of the toe end of the upper outspread on the wipers in the lasting operation. This retarder is curved to extend around the end and along portions of the sides of the toe, and it is secured by two screws 32 (Fig. 3) to a holder 34. Threaded in the holder are two screws 36 by which it is suspended,

together with the retarder 30, on downwardly extending arms of a pair of L-shaped members 38 with provision for turning movement about the axes of the screws. The members 38 have forwardly extending arms mounted for upward and downward swinging movements on the opposite ends of a rod 40 extending through holes formed in portions of the holder 4 located at opposite sides of a recess 42 in the holder. The rod thus extends widthwise of the shoe in a location opposite the bottom of the forepart of the shoe. A head (Fig. 1) on one end of the rod 40 and suitable means (not shown) on its other end confine the members 38 on the rod. Extending through these members between their opposite ends is also a rod 44 by which they are pivotally connected to the lower ends of a pair of upwardly extending links 46 joined together by a crosspiece 48. The upper ends of the links are pivotally connected by a pin 50 to an arm 52 fast on a rock-shaft 54 mounted in bearings in the frame. Another arm 56 (Fig. 1) fast on this rockshaft is connected by a link 58 to one arm of a bell-crank lever 60 rotatable on a shaft 62, the other arm of the bell-crank lever having thereon a roll 64 in engagement with the periphery of a cam 66 fast on a cam shaft 68 which, as shown in the previously mentioned Letters Patent, carries the cams for operating other portions of the machine. The roll 64 is held normally in engagement with the cam 66 by a spring 70 connected to the bell-crank lever 60 and also by a spring 72 connected at one end to an arm 74 fast on the rockshaft 54 and at the other end to a lever 76 whereby the tension of this spring may be adjustably varied. The construction is such that when the parts are in their initial positions the retarder 30 is so located as to position the shoe lengthwise by engagement with the end face of the last when it is presented to the machine, as illustrated in Fig. 4, and in view of the curved shape of the retarder it also serves to position the extreme toe end of the shoe laterally. After the wipers have been swung upwardly far enough to clamp the upper against the retarder (Fig. 5) they serve by their further upward movements to lift the retarder in the course of the upwiping operation against the resistance of the springs 70 and 72, the roll 64 being thereby moved somewhat away from the periphery of the cam 66. It will be understood that in this operation the retarder is pressed on the upper by the springs 70 and 72 and that the pressure thus applied to the upper may be varied by varying the tension of the spring 72 by means of the lever 76. After the upwiping operation, and preferably just after the wipers begin their movements to wipe the marginal portion of the upper inwardly over the insole, a rise *a* on the cam 66 engages the roll 64 and moves the retarder farther upwardly away from the wipers to release the margin of the upper. In the return of the parts to starting positions after the lasting operation a drop *b* on the cam 66 arrives in a position opposite the roll 64, whereupon the retarder is returned to its initial position by the springs 70 and 72.

To afford better insurance that the margin of the insole will not be deflected upwardly away from the bottom of the last in the upwiping operation the machine is further provided with a hold-down 78 arranged to engage the marginal portion of the toe end of the insole in a location between the edge of the insole and the plate 2. This hold-down is supported by a block 80 mounted for swinging movements heightwise of

the shoe about the same rod 40 as the members 38, the block extending into the recess 42 in the holder 4. The holdown is mounted on a screw 82 which is threaded in a downwardly extending portion of the block 80, and it is free for limited tipping movement about the screw to permit it to adjust itself to the insole and the last. A screw 84 threaded in the block 80 is arranged to engage a rearwardly extending surface 86 on the holder 4 to position the block adjustably with the holdown at the proper height relatively to the plate 2. The block is held yieldingly in the position thus determined by means of a spring 88 extending through an opening in the holder 4, one end of the spring bearing against the block and the other end against a bar 90. Extending through this bar and threaded in the holder 4 are two screws 92, one of which is shown in Fig. 2 and the other in Fig. 4, by means of which the bar may be adjusted to vary the compression of the spring 88. The holdown 78 is withdrawn from engagement with the insole against the resistance of the spring 88 substantially simultaneously with the withdrawal of the retarder 40 from the wipers. For this purpose a rearwardly extending lug 94 on the block 80 is provided with a screw 96 arranged to be engaged by the cross-piece 48 on the links 46. The crosspiece is carried substantially into engagement with the screw in the upwiping operation, after which further movement of the links 46 to withdraw the retarder 30 from the wipers serves also to withdraw the holdown 78 from the insole.

The manner of operation of the machine, in so far as it is of interest with reference to the present invention, will now be briefly summarized. The operator presents a shoe to the machine with the bottom of the forepart of the insole in engagement with the plate 2, rubber latex or other suitable cement having been applied to the margin of the toe-end portion of the insole and, if the toe end of the upper has not been trimmed, to the margins of the several layers of the upper materials. If, as is sometimes the practice, the upper has been trimmed so that only its outer layer will overlie the insole to any substantial extent, that layer only will have received the cement. In thus presenting the shoe the operator positions the toe-end face of the last against the retarder 30 which, by its engagement with the last, positions the shoe lengthwise and also positions its extreme toe end laterally, the toe end of the upper being outspread below the retarder and above the wipers. As shown in Fig. 4, the retarder at this time is prevented from swinging about the axes of the screws 36 by engagement of its holder 34 with the downwardly extending portion of the block 80. The position of the ball portion of the shoe laterally may be further determined by sight with reference to the portion of the plate 2 which is within view of the operator. When the shoe is in proper position the operator starts the power operation of the machine, whereupon the toe rest 26 is moved upwardly to clamp the shoe against the plate 2 (Fig. 4) and the heel rest (not shown) is moved into engagement with the heel-end face of the shoe. The wipers 28 are then advanced and closed and are swung upwardly to bring their edges into positions for effectively wiping the upper heightwise of the last, the upper being clamped on the top of the wipers by the retarder 30 substantially at the time when their edges arrive in those positions (Fig. 5). Thereafter, as the wipers continue their upward movements to

wipe the upper heightwise of the last, they lift the retarder against the resistance of the springs 10 and 72, the retarder-supporting members 38 swinging upwardly about the rod 40 and the roll 64 being moved away from the periphery of the cam 66. In the upwiping operation, therefore, the wipers and the retarder cooperate to apply a pull to the upper while permitting its marginal portion to slip inwardly between them, the clamping pressure applied to the upper and therefore the force of the pull thereon being determined by the adjustment of the tension of the spring 72. Since the retarder may swing about the axes of the screws 36, i. e., about an axis extending widthwise of the shoe, when its holder 34 is carried away from the block 80, it adjusts itself to the wipers in the upwiping operation and is not angularly displaced relatively to the wipers by the swinging movements of its supporting members 38. At the end of the upwiping operation the crosspiece 48 between the links 46 has been carried substantially into engagement with the screw 96, as illustrated in Fig. 6. After the completion of the upwiping operation the wipers are further advanced and closed to wipe the marginal portion of the upper inwardly over the insole. Shortly after the beginning of such inward movements of the wipers, when they are positioned substantially as further illustrated in Fig. 6, the rise α on the cam 66 engages the roll 64 and acts through the mechanism connected to the members 38 to swing these members farther upwardly about the rod 40 and thus to withdraw the retarder 30 from the upper and the wipers. At the same time the crosspiece 48 by its action on the screw 96 swings the block 80 about the rod 40 to withdraw the holdown 78 from the insole out of the paths of the wipers. As the wipers continue their inward movements they wipe the upper inwardly over the cement-coated margin of the insole and press a portion of its margin in upstanding position against the plate 2. While the wipers are holding the upper in overwiped position the machine preferably comes to a stop at the same time in the cycle as the stop which is provided by the disclosure of Letters Patent No. 2,160,846 to enable the operator, in accordance with that disclosure, to apply a binder wire about the toe of the welt shoe therein shown. If desired, the operator may similarly apply a binder wire w at this time to hold the upper until the cement has more firmly set, fastening the wire to a tack t at one side of the shoe bottom and pulling it inwardly under the wipers during the pause in the cycle of the machine. He then starts the machine again, whereupon the wipers are partially retracted to permit the wire to be pulled farther inward and are then operated to force the wire more firmly against the margin of the upper supported by the plate 2; as shown in Fig. 7, the machine coming once more to a stop to permit the operator to fasten the wire to another tack at the other side of the shoe bottom in accordance with the further disclosure of the above-mentioned Letters Patent. Thereafter the machine is started a third time, whereupon the parts are returned to starting positions and the shoe is released. It will be understood that eventually the binder wire is removed and the upstanding margin of the upper is trimmed off by a hand knife or any other suitable means.

Having described the invention, what I claim as new and desire to secure by Letters Patent of the United States is:

1. In a lasting machine, the combination with wipers movable heightwise of a last to perform an upwiping operation on the toe end of an upper on the last, of a retarder for clamping the marginal portion of the upper outspread on the wipers, said retarder being arranged to engage the toe end of the last exteriorly of the last bottom to position the shoe when it is presented to the machine and being supported for movement heightwise of the last by the wipers in the upwiping operation.

2. In a lasting machine, the combination with wipers movable heightwise of a last to perform an upwiping operation on the toe end of an upper on the last, of a retarder for clamping the marginal portion of the upper outspread on the wipers, said retarder being arranged to engage the toe-end face of the last to position the shoe lengthwise when it is presented to the machine and being supported for movement heightwise of the last in response to pressure of the upper thereon in the upwiping operation, and spring means arranged to press the retarder on the upper and yieldable to permit such movement of the retarder heightwise of the last.

3. In a lasting machine, the combination with wipers movable heightwise of a last to perform an upwiping operation on the toe end of an upper on the last, of a retarder for clamping the marginal portion of the upper outspread on the wipers, said retarder being curved to extend about the toe end of the last and being arranged to engage the last to position its toe end lengthwise and laterally when the shoe is presented to the machine, and spring means against the resistance of which the retarder is movable heightwise of the last by the wipers in the upwiping operation.

4. In a lasting machine, the combination with wipers movable heightwise of a last to perform an upwiping operation on the toe end of an upper on the last, of a retarder for clamping the marginal portion of the upper outspread on the wipers, and means for maintaining said retarder initially in position to serve as an abutment opposite the toe-end face of the last for positioning the shoe lengthwise when it is presented to the machine, the retarder being movable from that position heightwise of the last with the wipers in the upwiping operation.

5. In a lasting machine, the combination with wipers movable heightwise of a last to perform an upwiping operation on the toe end of an upper on the last, of a retarder for clamping the marginal portion of the upper outspread on the wipers, said retarder being arranged to engage the toe end of the last exteriorly of the last bottom to position the shoe when it is presented to the machine, and a support for the retarder mounted for swinging movement heightwise of the last in the upwiping operation about an axis positioned opposite the bottom of the forepart of the last.

6. In a lasting machine, the combination with wipers movable heightwise of a last to perform an upwiping operation on the toe end of an upper on the last, of means arranged to be positioned opposite the bottom of the last for positioning the shoe heightwise relatively to the wipers, a retarder for clamping the marginal portion of the upper outspread on the wipers, said retarder being arranged to engage the toe-end face of the last to position the shoe lengthwise when it is presented to the machine, and a support for said retarder mounted on said first-

named positioning means for swinging movement heightwise of the last about an axis extending widthwise of the last in response to pressure of the upper on the retarder in the upwiping operation.

5 7. In a lasting machine, the combination with wipers movable heightwise of a last to perform an upwiping operation on the toe end of an upper on the last, of a retarder for clamping the marginal portion of the upper outspread on the wipers about the toe end of the last, said retarder being arranged to engage the toe end of the last exteriorly of the last bottom to position the shoe when it is presented to the machine, and a support for the retarder mounted for swinging movement heightwise of the last in the upwiping operation about an axis extending widthwise of the last in a location opposite the bottom of the forepart of the last, the retarder being movably connected to said support to prevent it from being angularly displaced relatively to the wipers by the swinging of the support.

25 8. In a lasting machine, the combination with wipers movable heightwise of a last to perform an upwiping operation on the toe end of an upper on the last, of a retarder for clamping the marginal portion of the upper outspread on the wipers about the toe end of the last during the upwiping operation, a member located opposite the bottom of the forepart of the last and stationary during the operation of the machine, and a support for said retarder mounted on said member for swinging movement heightwise of the last about an axis located opposite the bottom of the forepart of the last in response to pressure of the upper on the retarder in the upwiping operation, the retarder being movably connected to said support to prevent it from being angularly displaced relatively to the wipers by the swinging of the support.

30 9. In a lasting machine, the combination with wipers movable heightwise of a last to perform an upwiping operation on the toe end of an upper on the last, of a retarder for clamping the marginal portion of the upper outspread on the wipers, means for maintaining said retarder initially in position to serve as an abutment opposite the toe-end face of the last for positioning the shoe lengthwise by engagement with the last when it is presented to the machine, the retarder being movable from that position heightwise of the last by the wipers in the upwiping operation, and additional means for moving the retarder farther heightwise of the last away from the wipers after the upwiping operation.

35 10. In a lasting machine, the combination with wipers movable heightwise of a last to perform an upwiping operation on the toe end of an upper on the last, of a retarder for clamping the marginal portion of the upper outspread on the wipers, controlling mechanism connected to said retarder, spring means arranged to act on said mechanism to maintain the retarder initially in position to engage the toe-end face of the last and thereby to position the shoe lengthwise when it is presented to the machine, said spring means being yieldable to permit movement of the retarder heightwise of the last by the wipers in the upwiping operation, and a cam arranged to act thereafter through said mechanism to move the retarder farther heightwise of the last away from the wipers.

40 11. In a lasting machine, the combination with wipers for performing an upwiping operation on the toe end of an upper on a last and for there-

after wiping the marginal portion of the upper inwardly over an insole on the last, of a retarder for clamping the marginal portion of the upper outspread on the wipers, a holddown arranged to engage the margin of the toe end of the insole to press it on the bottom of the last, and means for moving said retarder and holddown substantially simultaneously heightwise of the last at a predetermined time in the lasting operation to withdraw them respectively from the wipers and the insole.

12. In a lasting machine, the combination with wipers for performing an upwiping operation on the toe end of an upper on a last and for thereafter wiping the marginal portion of the upper inwardly over an insole on the last, of a retarder for clamping the marginal portion of the upper outspread on the wipers, a holddown arranged to engage the margin of the toe end of the insole to press it on the bottom of the last, mechanism movable to withdraw said retarder heightwise of the last from the wipers after the upwiping operation, and means substantially into engagement with which a portion of said mechanism is movable in the upwiping operation for also withdrawing the holddown from the insole by said mechanism when the retarder is withdrawn.

13. In a lasting machine, the combination with wipers for wiping the toe-end portion of an upper on a last into lasted position, of a retarder for clamping the marginal portion of the upper outspread on the wipers, a holddown arranged to engage the margin of the toe end of an insole on the last to press it on the bottom of the last, and supports for said retarder and holddown each mounted for swinging movement heightwise of the last about an axis located opposite the bottom of the last.

14. In a lasting machine, the combination with wipers for wiping the toe-end portion of an upper on a last into lasted position, of a retarder for clamping the marginal portion of the upper outspread on the wipers, a holddown arranged to engage the margin of the toe end of an insole on the last to press it on the bottom of the last, supports for said retarder and holddown each mounted for swinging movement independently of the other heightwise of the last about an axis located opposite the bottom of the last, and means for thus swinging said supports to withdraw the retarder and holddown respectively from the wipers and the insole in predetermined time relation to the operation of the wipers.

15. In a lasting machine, the combination with wipers for wiping the toe-end portion of an upper on a last into lasted position, of means arranged to be positioned opposite the bottom of the last for positioning the shoe heightwise relatively to the wipers, a retarder for clamping the

marginal portion of the upper outspread on the wipers, a holddown arranged to engage the margin of the toe end of an insole on the last to press it on the bottom of the last, supports for said retarder and holddown mounted for swinging movements independently of each other heightwise of the last about a common axis on said shoe-positioning means, and means for thus swinging said supports to withdraw the retarder and holddown respectively from the wipers and the insole in predetermined time relation to the operation of the wipers.

16. In a lasting machine, the combination with wipers movable heightwise of a last to perform an upwiping operation on the toe end of an upper on the last and movable thereafter to wipe the marginal portion of the upper inwardly over an insole on the last, of a retarder for clamping the marginal portion of the upper outspread on the wipers, a holddown arranged to engage the margin of the toe end of the insole to press it on the bottom of the last, the retarder being movable relatively to the holddown heightwise of the last by the wipers in the upwiping operation, and means for thereafter withdrawing the retarder and the holddown substantially simultaneously heightwise of the last from the wipers and the insole respectively.

17. In a lasting machine, the combination with wipers movable heightwise of a last to perform an upwiping operation on the toe end of an upper on the last and movable thereafter to wipe the marginal portion of the upper inwardly over an insole on the last, of a retarder for clamping the marginal portion of the upper outspread on the wipers, a holddown arranged to engage the margin of the toe end of the insole to press it on the bottom of the last, the retarder being movable relatively to the holddown heightwise of the last by the wipers in the upwiping operation, mechanism for thereafter moving the retarder farther heightwise of the last away from the wipers, and means substantially into engagement with which a portion of said mechanism is carried by the movement of the retarder in the upwiping operation for also withdrawing said holddown from the insole by said mechanism when the retarder is withdrawn from the wipers.
